DESIGN FOR A DIESTOCK

William A. Phillis, Warren, Ohio, assignor to
Beaver Pipe Tools, Inc., Warren, Ohio, a corpo-
ration of Ohio

Application July 31, 1940, Serial No. 94,068

Term of patent 14 years

To all whom it may concern:

Be it known that I, William A. Phillis, a citizen
of the United States, residing at Warren, in the
county of Trumbull and State of Ohio, have in-
vented a new, original, and ornamental Design
for a Diestock, of which the following is a speci-
fication, reference being had to the accompany-
ing drawing, forming a part thereof.

In the drawing,

Fig. 1 is a top plan of the diestock showing my
new design;

Fig. 2 is a side elevation thereof, the opposite
side being similar;

Fig. 3 is a bottom plan thereof.

I claim:

The ornamental design for a diestock, substan-
tially as shown and described.

WILLIAM A. PHILLIS.
